UNITED STATES PATENT OFFICE.

DONALD FOREMAN, OF PORTLAND, OREGON.

GAME APPARATUS.

Application filed March 25, 1924. Serial No. 701,727.

To all whom it may concern:

Be it known that I, DONALD FOREMAN, a citizen of the United States, residing at Portland, in the county of Multnomah and 5 State of Oregon, have invented certain new and useful Improvements in Game Apparatus, of which the following is a specification.

This invention relates to game apparatus 10 and its object is to provide a simple structure which may be cheaply constructed but provides a game of great difficulty to solve.

In accordance with the invention, there is provided a board which may be of square 15 or similar contour and has sunken in one surface in chosen order a regular series of sockets adapted to each receive a pin, which pin is made of sufficiently smaller diameter than the socket to move thereinto with great 20 freedom but still in a manner to maintain an upright position. Each pin is of a diameter and length to rise above the surface of the board for a distance permitting the pin to be readily grasped, but the pin itself 25 is of regular diameter throughout, so that the grasping of the pin, while quite possible is rendered more or less difficult by the relatively small diameter of the pin and the relatively slight extension of the pin above 30 the upper surface of the board when the pin is seated in a socket.

Each socket is numbered and each pin is also numbered while the number of pins employed is one less than the number of 35 sockets provided.

When the game is to be played, the full 40 number of pins is distributed in the sockets or holes, but as the number of pins is one less than the number of sockets or holes, one of the sockets remains empty.

The pins are placed in the sockets indiscriminately and the problem is to rearrange 45 the pins in the sockets in regular order with the pins shifted from the mixed up order in which they are originally placed in the sockets to the final regular order desired, the rearrangement being accomplished by jumping the pins over each other until the new regular order is accomplished this 50 being brought about by observance of the numbers on the pins and the numbers adjacent to the sockets.

The invention will be best understood 55 from a consideration of the following detailed description taken in connection with the accompanying drawing, forming part

of this specification, with the understanding that the invention is not confined to any strict conformity to the showing of the drawings, but may be changed and modified 60 so long as such changes and modifications mark no material departure from the salient features of the invention as expressed in the appended claims.

In the drawings:—

Figure 1 is a plan view of the instrument board.

Fig. 2 is a perspective view of the board with the top ends of the pins shown in the 70 sockets but without orderly arrangement.

Fig. 3 is a perspective view of one of the pins.

Referring to the drawings, there is shown a game board 1 having produced in one surface an orderly series of sockets 2 which 75 may extend to an appropriate depth and in these sockets are pins 3 each of greater length than the depth of the socket and of slightly less diameter so that a pin when lodged in a socket may be readily grasped 80 by the fingers of the human hand and changed from one socket to another without binding in the sockets.

In the particular arrangement shown in the drawings, the game board is provided 85 with sixteen sockets arranged in rows of four sockets each.

Each socket is provided on the face of the board with a designating number 4 and each pin is provided on the visible end with a 90 designating number 5.

In the arrangement of the board, there are sixteen sockets but in playing the game but fifteen pins are employed and these pins are numbered from one to fifteen, inclusive, 95 wherefore one of the sockets remains empty and this may be the socket 16, but in the particular arrangement shown in Fig. 2, the socket 7 may be the socket which remains empty on beginning the playing of the game 100 with the other pins, one to fifteen, distributed among the sockets, leaving the socket in the particular instance shown, that numbered 7, empty.

The game is played by moving one of the pins surrounding the empty socket 7 to said socket and depositing it therein. This leaves a neighboring socket empty and then the pin from the neighboring socket is moved into the socket 7 or the one emptied 110 in filling the socket 7 and so the movement throughout the surface of the board begins

progressively until there is a rearrangement effected of the pins and sockets, it being necessarily in the playing of the game that to obtain the progressive movement, the pins 5 shall be jumped from one socket to a neighboring empty socket and so on so long as the playing progresses.

The problem to be solved is to rearrange the pins in consecutive order from one to 10 fifteen, which movement is of acknowledged difficulty and sometimes proves to be impossible.

In a practical embodiment of the invention, the board may measure about five 15 inches square with the sockets 2 measuring seven-sixteenths of an inch diameter and the pins 3 being each seven-eighths of an inch long and three-eighths of an inch in diameter, the number of sockets being sixteen, 20 while the number of pins is fifteen.

A convenient thickness for the board may be three-quarters of an inch leaving the length of each pin somewhat less than the difference between three-quarters of an inch, 25 the thickness of the board, and seven-eighths of an inch, the length of the pin, this providing sufficient grasping space for the projecting end of the pin.

The sockets are of constant diameter 30 throughout their length and the pins also are of constant diameter.

What is claimed is:—

1. A game apparatus comprising a polygonal-shaped base provided on its upper 35 face with four transversely extending spaced rows of spaced shallow sockets, each row consisting of four sockets, the sockets of one row arranged in alignment with respect to the sockets of an adjacent row, 40 means on the upper face of said base in proximity to each of the sockets of each row to consecutively designate the sockets of the row, the designations for the sockets of one row being different from the designations

for the sockets of an adjacent row, a set of 45 removable socket entering pins, said set of a number less one than the combined number of sockets of the four rows, each of said pins of a height greater than the depth of any one of the sockets and having a flat top, 50 and means on the top of each of said pins to provide a numerical designation therefor, the designation on each of said pins being different and corresponding to a designation of a socket. 55

2. A game apparatus comprising a polygonal-shaped base provided on its upper face with four transversely extending spaced rows of spaced shallow sockets, each 60 row consisting of four sockets, the sockets of one row arranged in alignment with respect to the sockets of an adjacent row, means on the upper face of said base in proximity to each of the sockets of each row to consecutively designate the sockets of the 65 row, the designations for the sockets of one row being different from the designations for the sockets of an adjacent row, a set of 70 removable socket entering pins, said set of a number less one than the combined number of sockets of the four rows, each of said pins of a height greater than the depth of any one of the sockets and having a flat top, 75 and means on the top of each of said pins to provide a numerical designation therefor, the designation on each of said pins being different and corresponding to a designation of a socket, each of said sockets being circular, and each of said pins being cylindrical and of the same diameter throughout 80 and of a diameter with respect to each socket to provide for the loose seating of a pin in a socket, thereby providing for the convenient entry and removal of the pins.

In testimony whereof, I affix my signature hereto. 85

DONALD FOREMAN.
